CLAIM

The ornamental design for an all-terrain vehicle, as shown and described.

DESCRIPTION

FIG. 1 is a front elevation view of an all-terrain vehicle according to the present application, showing our new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a top, front, and right side perspective view thereof; and,

FIG. 7 is a top, rear, and left side perspective view thereof. The broken lines in the drawings depict portions of the product that form no part of the claimed design.
